[57] CLAIM

The ornamental design for a tumbler or similar article, substantially as shown and described.

DESCRIPTION

FIG. 1 is a top front perspective view of a tumbler or similar article showing my new design;

FIG. 2 is a right side elevational view thereof;

FIG. 3 is a rear elevational view thereof;

FIG. 4 is a left side elevational view thereof;

FIG. 5 is a fragmentary sectional view thereof taken on line 5—5 of FIG. 4; and

FIG. 6 is a fragmentary developed plan view of the surface ornamentation thereof.

The top and bottom plan views of the tumbler are of circular configuration. The surface ornamentation that would be visible through the transparent side walls has been omitted from FIGS. 2, 3, 4 and 5 for convenience of illustration.
